UNITED STATES PATENT OFFICE.

HENRY T. CHILDRESS, OF HALLETTSVILLE, TEXAS.

RAZOR-STROP HOLDER.

1,243,710.

Specification of Letters Patent. Patented Oct. 23, 1917.

Application filed May 9, 1917. Serial No. 167,502.

To all whom it may concern:

Be it known that I, HENRY T. CHILDRESS, a citizen of the United States, residing at Hallettsville, in the county of Lavaca and State of Texas, have invented a new and useful Razor-Strop Holder, of which the following is a specification.

The present invention relates to a razor strop holder, and aims to provide a novel and improved device for winding up and housing a razor strop when not in use, the strop being readily withdrawn when needed.

It is the object of the invention to provide a razor strop holder of simple and inexpensive construction, which can be readily and cheaply manufactured, and which will be practical and efficacious in use.

A further object of the invention is the provision of a razor strop holder, having means whereby the strop can be readily reversed to use either side thereof.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

The invention is illustrated in the accompanying drawing, wherein:

Figure 1 is a side elevation of the improved holder.

Fig. 2 is a section thereof on the line 2-2 of Fig. 3, with the strop rolled up.

Fig. 3 is a section on line 3-3 of Fig. 1, with the strop withdrawn.

The casing which is preferably constructed of sheet metal, embodies the side plates 1, having the tapered extensions 2, and a plate 4 curved to fit the edges of the side plates 1. The ends of the plate 3 are flush with the extensions 2, providing a mouth or opening 3 for the casing. In order to attach the plates together, the marginal portions of the plates 1 are provided with outward flanges 5, and the edges of the plate 4 are bent back inwardly, as at 6, to embrace the flanges 5.

As a means for supporting the casing upon the arm of a barber's chair or from any other suitable support, a curved supporting plate 7, fitting the plate 4 of the casing, is provided at its ends with bent back

lips 8, fitting slidably upon the bent back edge portion 6 of the plate 4, and the longitudinal side edges of the plate 7 are provided with flanges or lips 9 for attachment to the arm of a chair or other support. The curved portions 6 of the casing in engaging the supporting plate under the overhanging lips or flanges 8, enables the casing to be adjusted rotatably about its axis, through about an angle of 180°, to direct the mouth 3 of the casing in the direction desired.

A drum or reel 10 is rotatable within the casing coaxial therewith, upon a spindle 11 in the casing and extending through the side plates 1, a retaining nut 12 or other suitable retaining element being engaged to one end of the spindle 11 for holding it in place. The drum 10 is provided at its opposite end with a recess 13 in which a coiled torsional spring 14 is disposed, the inner end of the spring being engaged to the drum and the outer end being secured to a disk 15 engaged non-rotatably with a non-circular portion 16 of the spindle 11 which engages the respective side plate of the casing to prevent the spindle 11 and disk 15 from rotating.

The drum 10 is provided intermediate its ends with an annular groove 17 for receiving a short strap 18 that has one end secured to the drum within the groove, as at 19. The strap 18 is just sufficiently long to extend from the drum out through the mouth or opening 3, as seen in Fig. 3, and a transverse strip 20 is swiveled as at 21, to the free end of the strap 18 for the attachment thereto of one end of the strop 22. The strop is clamped by means of screws 23 or otherwise to the strip 20, and is provided at its free end with a suitable handle 24.

A pair of rollers 25 are mounted transversely within the mouth 3 upon spindles 26, having their terminals engaged with the extensions 2. The strop 22 passes between the rollers 25 in being withdrawn and wound up.

When the strop is released, the spring 14, in rotating the drum 10, will wind the strop on the drum, so that the strop will be held within the casing. The strap 18 is wound on the drum in the groove 17, so that the strop can wind promptly onto the drum. To use the strop, it is pulled from the casing, thereby winding up the spring 14, and when the strop is pulled out of the casing,

as seen in Fig. 3, it can be reversed to use either side thereof, but the strip 20 must be moved into registration with the slot between the rollers 25 before the strop can be pulled into the casing.

Having thus described the invention, what is claimed as new is:

1. A razor strop holder embodying a casing comprising side plates and a curved plate having its edges engaged to the edges of the side plates, a drum between and carried by the side plates, spring means for rotating the drum, and a supporting member having portions slidably engaging said edges of the plates.

2. A razor strop holder embodying a casing comprising side plates and a curved plate having its edges bent back into engagement with the side plates to fasten them together, a drum between and supported by the side plates, spring means for rotating the drum, and a supporting member fitting the curved plate and having bent back portions slidably engaging the aforesaid bent back edges.

3. A razor strop holder embodying a casing having an opening, a spring pressed drum mounted rotatably within the casing,

a razor strop to be wound upon the drum, and a connection between the strop and drum permitting the strop to be reversed when withdrawn from the casing.

4. A razor strop holder embodying a casing having an opening, a spring-pressed drum mounted within the casing, a strap connected to the drum to move through said opening, and a strop swiveled to the end of the strap to be wound upon the drum and adapted to be reversed when withdrawn from the casing.

5. A razor strop holder embodying a casing having an opening, a spring-pressed drum mounted within the casing, a strap connected to the drum to move through said opening, a transverse strip swiveled between its ends to the end of said strap, and a strop secured to said strip to be wound upon the drum.

In testimony that I claim the foregoing as my own, I have hereto affixed my signature in the presence of two witnesses.

HENRY T. CHILDRESS.
